SOAP RECEPTACLE

Joseph J. Settle, 1319 N. Fashion Lane 1,
Anaheim, Calif. 92806

Original design application Nov. 27, 1970, Ser. No.
26,182, now Patent No. 224,028, dated June 27,
1972. Divided and this application Feb. 7, 1972,
Ser. No. 232,650

Term of patent 14 years

Int. Cl. D6—06

U.S. Cl. D6—89

FIG. 1.

FIG. 2.

FIG. 1 is a perspective view taken from the top, front and left side of a soap receptacle embodying my new design, the right side being the same as the side shown;

FIG. 2 is a perspective view of a modified form of the soap receptacle shown in FIG. 1.

This is a division of design application Ser. No. D. 26,182, filed Nov. 27, 1970, now design Pat. No. D. 224,028, issued June 27, 1972.

I claim:

The ornamental design for a soap receptacle, substantially as shown and described.
